ADAPTER FOR VALVE BAGS

Andrew J. Verwys, Oswego, N. Y.

Application August 14, 1934, Serial No. 739,725

6 Claims. (Cl. 150—9)

This invention relates to improvements in valve bags, and has particular reference to novel and simple means for controlling the pneumatic filling of the bags, as well as obviating subsequent leaking or sifting of the contents of the bags through the valves.

The primary object of the invention is to prevent the supercharging of the bags during the filling operations with an excess of pressure that 10 frequently unduly inflates and distorts or balloons the bags beyond the extent normal to the proper filling thereof; the said preventive means comprising flexible fibrous adapters or elements, having the form of split tubes, which may be 15 telescopically and permanently inserted in the valve openings, before or after the bag ends are sewed or pasted; the adapters for both styles of valve bags being made from common blanks, and having their outer end portions pasted to the cor- 20 responding portions of the inner surfaces of the mouths of the valves, while their inner or opposite ends preferably remain loose, and the whole of said adapters being free to expand with the valves when the filling pipes are inserted there- 25 in, and therefore occupy the usual spaces between the inner walls of the valves and filling pipes, like flexible or pliable bushings, which fit the valve openings with sufficient looseness to afford more or less free vents between the pipes and 30 adapters, via which any excess or accumulated pressure may bleed away through the bushed valves while the bags are being filled. After the bags are filled, the pipes are withdrawn, and at the start of these withdrawal movements, hooks 35 formed on the tips of the pipes engage the free or unpasted ends of the fibrous adapters and draw said ends back towards the mouths of the valves, and in so doing, these loose ends are crumpled and caused to virtually telescope the pasted ends 40 until the hooks, owing to the increased resistance offered by said pasted ends, tear the fiber and come free. This leaves the passage through the valves substantially clogged with waddings of the crumpled adapters, which not only effectually 45 prevent subsequent sifting or leaking of the contents of the bags, but also obviate all danger of atmospheric moisture entering the filled bags and impairing the quality and destroying the usefulness of the various commodities with which the 50 bags are loaded.

I attain these objects by the means set forth in the detailed description which follows, and as illustrated by the accompanying drawing, in which—

55 Figure 1 is a broken side elevation of the valve-

end of a sewed bag, folded to form the valve. Fig. 2 is a broken vertical section, taken on line 2—2 of Fig. 4, showing the adapter in the form of a flat tube inserted in the valve. Fig. 3 is a central vertical section, taken on line 2—2 of Fig. 4, showing the filling pipe being withdrawn and in the act of crumpling the free end of the adapter. Fig. 4 is a broken elevation of a sewed bag, with the adapter of Fig. 13 operatively disposed in the valve. Fig. 5 is a broken side elevation of a sewed bag after the same has been filled, and the filling pipe removed, showing the wadding of the adapter left in the mouth of the bag. Fig. 6 is a central vertical section through the valve of a pasted satchel form of bag, and a 15 broken sectional view of the filling pipe, taken on line 6—6 of Fig. 7, showing the pipe in the act of being withdrawn from the valve and effecting the initial crumpling of the adapter of Fig. 14. Fig. 7 is a broken end elevation of the 20 pasted bag with the adapter bushing the valve, and a cross-sectional view of the filling pipe. Fig. 8 is a plan view, showing the initial folding of the pasted bag blank, the valve flaps being ex- 25 tended, also showing the broken lines along which said flaps may be folded to complete the valve. Fig. 9 is an enlarged plan view showing the valve flaps disposed at right angles to the bottom of the valve, and the adapter of Fig. 14 resting on the bottom between the flaps. Fig. 10 is an enlarged 30 elevation taken in the direction of the arrow in Fig. 9. Fig. 11 is an enlarged broken plan view, showing the valve flaps folded inwardly, overlapped and pasted; also showing the wadding of the adapter protruding from the mouth of the 35 valve, following the withdrawal of the filling pipe. Fig. 12 is a diagrammatical plan of the common blank from which the adapters may be formed prior to their insertion in both the sewed and 40 pasted bags. Fig. 13 is a view showing the folding of the said blank for insertion into the sewed bag. Fig. 14 is a view of a different folding of the blank for insertion in the pasted bag. And Fig. 15 is a vertical cross-section, taken on line 45 15—15 of Fig. 3, showing the natural flare of the wings to provide free escape of the accumulated air pressure from the bag during the filling thereof.

The bags referred to herein, are invariably made by high-speed machinery, from fiber tubes comprising from one to five or six plies, and it frequently happens that certain portions of the bags unavoidably become more or less distorted. These defects are quite noticeable in the manufacture 50 of the integral valves of both sewed and pasted 55

- 5 bags, and interfere with the proper and rapid filling of the bags. In some cases, the passages through the valves are of too small caliber, and this causes the air pressure by which the various 10 products are forced into the bags, to accumulate in and unduly expand or balloon the bodies of the bags, which not only slows down the filling, but strains and so alters the shape of the filled bags, that they will not stack properly and evenly 15 when stored and transported. On the other hand, in many of the bags the valve openings are too large, and this results in the too free escape of the air around the filling pipe that carries with it more or less of the finely pulverized products, 20 which not only become wasted, but litter up the vicinity of the filling stations. The following description points out novel and simple means for overcoming these and other defects in both the sewed and pasted bags:
- 25 In the drawing, Figs. 1 to 5 inclusive, and Fig. 15, show similar broken tubular fragments, as 2, of a sewed valve bag, the stitches being indicated at 2', and the tube being folded in the usual manner to form a normally open valve, as A, shown 30 in Figs. 2, 3 and 4. This type of valve bag is preferably formed with lateral tucks, one of which, as 2a, plays an important part in the manufacture of the well-known Bates valve bags, wherein the top of the valve opening is virtually defined by the 35 stitching 2'.
- 35 The means for controlling the pneumatic filling of the sewed bags 2, as well as obviating the subsequent sifting or leaking of the contents of the bags, consists of a novel and simple flexible element or adapter, preferably in the form of a flat crinkled paper tube, as 3', which may be telescopically and permanently disposed in the valve A, either before or after the valve-end of the bag is sewed, as shown in Figs. 2, 3 and 4, the said element having its outer end portion pasted to the 40 corresponding portions adjacent the mouth of the valve, as shown at 3a in Figs. 2, 3 and 13. The adapter 3' is preferably formed from a peculiarly shaped standardized blank, as 3, shown diagrammatically in Fig. 12, which, when folded upon a central crease 3b, produces the adapter or bushing 3', of Fig. 13, the latter being formed near its free end with a weakening slot 3c, and with transverse weakening slits 3d, whose purposes will 45 be explained later on. In Fig. 4, the valve A, and also adapter 3', are shown partially expanded, so as to facilitate the proper and quick insertion of the pipe, as 4, by which the filling of the bag 2 is effected, usually by the aid of a strong air pressure. The pipe 4 preferably tapers from its middle towards its free end 4', and the under side of this portion is formed with a relatively large clear 50 downwardly facing opening 4a, through which cement, lime or other pulverized or granulated products may be blown into the body 2. The end 4' of the pipe 4 is preferably formed beak-shaped, as at 4b, to further aid in its insertion, and adjacent its top said end is also formed with a tooth or hook 4c, that faces the mouth a of the valve and 55 adapter. During the filling operations the pipe 4 is usually inserted in the valve to the extent shown by dotted lines in Figs. 3 and 6. When the bags are loaded with a predetermined amount of material, the pressure is shut off, and the pipe 4 is 60 withdrawn from the valve, and at the start of this latter movement, the hook 4c engages either the free end of the adapter 3', or else a shoulder, as 3e, of the weakening slot 3c, and draws said free end towards the mouth a (see initial crumpling 65 of adapter, as at 3f in Fig. 3), and in so doing,

causes said free end to telescope the pasted end of the adapter until the hook finally tears the fiber and comes free, the slits 3d facilitating crumpling. This leaves the mouth of the valve clogged with a wadding 3x of the crumpled adapter, as shown in Fig. 5, which effectually prevents sifting of the contents of the bag, as well as the infiltration of atmospheric moisture, through the valve opening, as explained.

When the bags are placed erect in the loading 10 position of Fig. 3, they are relatively light and entirely free from restraint of any nature. As the filling of the bags progresses, the weight of the load creates a downward strain on the whole bag 15 that acts to take up the normal slack throughout its entire length and tends to contract the normally free valve opening, and this results in the bag becoming supercharged with the accumulated pressure, that effects the ballooning of the tube, which the present invention is designed to 20 remedy.

When the blank 3 is folded along the crease 3b to form the adapter 3', the edge 3f is preferably free throughout its length. But after the adapter is inserted in the valve A, the pasting, as at 3a, 25 lessens the area of the adapter to the extent of the pasted area as shown in Fig. 2. This leaves the said edge, including the angular weakening wings x, free to flex and gape, as shown in Fig. 15, and thus provide a clear and ample opening that 30 serves to bleed off, to the atmosphere, any accumulated pressure, that might otherwise effect the over-expansion of the bag 2 through the adapter-bushed opening of the valve, as hereinabove referred to.

35

The multiply bags referred to herein are formed from relatively heavy and stiff sheets of jute fiber, which require deft handling in order to effect the several short folds of the valves. It is characteristic of most of these bags, that the valves immediately after being formed tend to gape, as shown somewhat exaggerated in Fig. 4, and this tendency persists to a considerable extent even after the bags are filled, and has been found to be the primary cause of much of the sifting 40 through the valves as A and B. To remedy this defect or fault, the newly made bags have heretofore been passed between press-rolls, which temporarily flatten the folds of the valve parts, reduce the extent of the gaping, and therefore 45 lessen the danger of leakage in which condition the valves remain until filling work begins. It develops, however, that the filling, which is effected pneumatically, acts to expand the bags in all directions, and in so doing, tends to enlarge 50 the valve openings and renew the danger of sifting, or the infiltration of atmospheric moisture which often impairs the quality and destroys the usefulness of the contents of the bags. From the foregoing, it appears that this type of paper bags 55 lacks any inherent quality or means to prevent either the escape of the contents, or the entrance of moisture, and that the several faults or defects complained of can only be remedied by the use of the present adapters, or other auxiliary elements 60 that will act to supplement the normal combination of parts of the present day valve bags.

65

In Figs. 6 to 11 inclusive, are shown the usual steps by which a plain pasted satchel fold valve bag, as 5, is constructed, in which Fig. 6 is a 70 central vertical section of the broken valve-end of the bag, 5, taken on line 6-6 of Fig. 7, which is an end elevation and partial vertical cross-section of the same. Fig. 8 shows the primary treatment of the tube 5, which consists of folding 75

inwardly a corner portion 5' to form the bottom 5a of the pasted bag, as B. The next step consists of creasing the extended parts in the direction of the long way of the valve, as at 5b, to form right and left flaps, as 5c-5d, which are ultimately folded towards each other, overlapped and pasted, as shown in Fig. 11, to complete the formation of the valve B. The flap 5d is shown treated with paste, as by the stippling 5e, to effect the adhesion of the flaps. Immediately following the creasing of Fig. 8, the flaps 5c-5d are preferably flexed upwardly at right angles to the bottom 5a of the valve, as shown respectively in plan in Fig. 9, and in elevation in Fig. 10. When this partial folding of the flaps is effected, the adapter 6 with paste applied, as at 3a, to its outer end is disposed flat upon the bottom of the valve, as shown in Figs. 9 and 10, in readiness to be permanently attached to the mouth of the valve, when the flaps are finally folded as shown in Fig. 11. The adapter 6 is preferably formed from the standardized blank 3, which when folded inwardly along the parallel creases 6', produces the adapter of Figs. 9, 10 and 14. In Fig. 7 the valve B and also the adapter 6 are shown fully expanded by the filling pipe 4x, by which the bag 5 may be filled, as explained. The filling pipe 4x is in all respects of the same construction and performs the same functions as the pipe 4, and when the filled bag is removed from the pipe, the latter acts in exactly the same way upon the adapter 6, and when the pipe 4x becomes free from the adapter, the crumpled portion of the adapter protrudes from the mouth 35 of the valve, as indicated at 6x in Fig. 11.

Having thus described my invention, what I claim, is—

1. A valve bag for use with a filling pipe provided with a hook or the like, having an adapter 46 folded upon itself and secured at the sides of its front portion to the valve and having an upwardly facing slot extending through its folded portion adjacent the inner end of the latter, to receive said hook whereby upon withdrawal of the pipe

the adapter will move therewith and be crumpled and disposed in the mouth of the valve to close same, said adapter having transverse weakened portions to facilitate crumpling.

2. A valve bag for use with a filling pipe provided with a hook or the like, having an adapter folded upon itself and secured at the sides of its front portion to the valve and having an upwardly facing slot extending through its folded portion adjacent the inner end of the latter, to receive 10 said hook whereby upon withdrawal of the pipe the adapter will move therewith and be crumpled and disposed in the mouth of the valve to close same.

3. A valve bag for use with a filling pipe provided with a hook or the like, having an adapter secured adjacent its outer end to the valve and having its inner end free, and means formed intermediate the ends of the adapter to engage said hook whereby upon withdrawal of the pipe, the 20 adapter will move therewith and be automatically crumpled and disposed in the mouth of the valve to close same.

4. A valve bag for use with a filling pipe provided with a hook or the like, having collapsible 25 closure means for the valve associated therewith, said closure means having a part formed to engage the hook and having weakened portions whereby upon withdrawal of the pipe the closure means will move therewith and be automatically 30 collapsed to fill and close the mouth of the valve.

5. A valve bag in accordance with claim 4, wherein the closure means has sides secured at their outer ends to the valve and having inner ends which incline upwardly and inwardly of the 35 bag.

6. A valve bag in accordance with claim 4, wherein the closure means is composed of a member folded upon itself to form a top and having the resultant sides secured at their outer ends to 40 the valve, and having inner ends which incline upwardly and inwardly of the bag.

ANDREW J. VERWYS.
